UNITED STATES PATENT OFFICE.

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY.

SEWING-MACHINE.

1,392,822.

Specification of Letters Patent.

Patented Oct. 4, 1921.

Original application filed November 27, 1916, Serial No. 133,625. Divided and this application filed January 16, 1918. Serial No. 212,042.

To all whom it may concern:

Be it known that I, ANDREW EPPLER, a citizen of the United States, residing at Lynn, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

This invention relates to waxed thread sewing machines, and more particularly to heating devices for such machines.

In sewing machines employing a waxed thread the needle thread is usually passed through a wax receptacle containing the melted wax, such receptacle being placed between the thread supply and the stitch-forming devices in order to impregnate the thread with wax before the seam is formed. The wax receptacle is usually located at a considerable distance from the stitch-forming devices, and in order to keep the waxed

thread in proper condition until it reaches the work, machines of this type are ordinarily provided with a system of heating devices arranged to heat up parts of the machine, including certain of the stitch-forming instrumentalities adjacent to and engaged by the thread as it passes from the wax receptacle to the work. In machines of this class the thread is looped about the needle by a looper secured in a looper carrier which has a compound motion so as to move the end of the looper in a substantially circular path about the needle. It is desirable that the looper should be heated to keep the thread in proper condition as it is laid about the needle, and difficulty has been experienced heretofore in providing means to keep the looping device properly heated.

It is accordingly the object of this invention to provide simplified and improved devices for heating the looper. With this object in view, a feature of the invention consists in the provision of a looper arranged to have a reciprocating, sliding and oscillatory motion about a horizontal bearing, in which at one end is formed a U-shaped steam passage which extends through the greater part of its length so as to heat said bearing, and by conduction constantly heat the looper.

In machines in which the looper is heated and the wax on the thread is in a melted condition as the thread passes through the looper, wax from the thread frequently drops upon and collects on the channel guide so that the operator has to remove it.

A further object of the invention is, therefore, to provide means for heating the channel guide. To this end the invention contemplates the provision of a channel guide having a sleeve or recess formed therein, in which is received a spring-pressed plunger held by such spring in engagement with the heated bearing of the looper in all positions of the channel guide, so as to heat said channel guide by direct metallic conduction from the heated looper bearing.

With these objects in view, other features of the invention consist in certain novel and improved constructions, arrangements and combinations of parts hereinafter described and particularly pointed out in the claims, the advantages of which will be obvious to those skilled in the art.

This application is a division of application Serial No. 133,625, filed November 27, 1916, and the invention is herein illustrated as embodied in the machine forming the subject-matter of said application.

The features of the present invention will be clearly understood from the following detailed description and accompanying drawings, in which Figure 1 is a side elevation of a sewing machine embodying the present invention, looking from the right; Fig. 2 is a side elevation looking from the left; Fig. 3 is a front elevation of parts of the machine, including particularly the mechanism for supporting and guiding the looper and for heating the looper and the channel guide.

The machine as shown is provided with the usual stitch-forming instrumentalities including a curved hook needle 1, an awl or feed point 2, a looper 3, a channel guide 4, a back gage 5, and a back rest 6. This mechanism is actuated by the main cam shaft A bearing the usual disk cams. The looper mechanism is shown particularly in Figs. 2 and 3. The looper 3 is fixed in a carrier 7 which comprises two sleeves 8 and 9 connected integrally and by a yoke 10. The sleeves are fitted to slide and rock upon a cylindrical bearing member 11 at the front

of the machine. This bearing member is supported at a point intermediate its ends in a bracket 12 which is screwed to the frame of the machine, the bearing member being fixed in the bracket by means of a cotter pin (not shown). The yoke 10 spans the bracket 12 so that the looper carrier may be moved both longitudinally and rotatably upon the bearing member, and the substantial distance which separates the point of engagement of the sleeves with the bearing member insures that there shall be a minimum degree of lost motion between the parts, and a correspondingly high degree of accuracy in the control of the movements of the looper.

The looper is actuated by the cams on the main shaft, and its traversing movements are produced by a cam lever 13 (Fig. 2) which carries at its lower end a roller engaging in a peripheral groove on one of the cam disks on the shaft A. At its upper end the cam lever is fixed to a forwardly extending rock shaft 14. A lever 15 depends from the forward end of the rock shaft, and the lower end of this lever is slotted as shown in Fig. 2 and embraces a block 16 which is pivoted on a stud 17 projecting from the yoke 10. Through this arrangement the rocking movements of the cam lever are transmitted to the looper carrier so as to slide the latter longitudinally on the bearing member 11, while by the use of the block 16 and the slotted end of the lever 15, interference with the rocking movements of the looper carrier is avoided. The rocking movements of the looper carrier are produced by a slide 18 which moves forwardly and rearwardly in a guideway on the frame of the machine. This slide carries at its rear end a roller 19 which engages in a groove in the vertical face of one of the cam disks, while the forward end of the slide is provided with a stud 20. This stud slides in a sleeve 21 at the upper end of the stem 22, and the stem is slidably mounted in an arm 23 projecting upwardly from the yoke 10. The forward and rearward movements of the slide 18 are thus communicated as rocking movements to the looper carrier, and the engagement of the stud 20 with the sleeve 21 is such as not to interfere with the longitudinal movements of the looper carrier. The stud 20 is of such length as to remain in engagement with the sleeve 21 in any position the looper carrier may occupy in its transverse movements.

The bearing member 11 is utilized as means for heating the looper. For this purpose a U-shaped steam passage 24 is formed within the bearing member, this passage being connected at its ends with pipes 25, through which steam or other heating fluid

may be introduced and discharged. The heat of the bearing member is conducted directly through the looper carrier to the looper.

In machines of the type in question wax from the thread frequently drops and collects upon the channel guide so that it is necessary for the operator to remove it. A feature of the present invention resides in the provision of means by which the channel guide is heated so that any wax which falls upon it is melted and may thus run away. In order to heat the channel guide, said channel guide is fixed to a plate 26, which in turn is adjustably fixed to the lever 27 by which the channel guide is supported and actuated in the same manner as in the patent to Eppler No. 1,108,560 issued August 25, 1914. As a convenient means for heating the channel guide, the plate 26 is provided with a sleeve or recess 28, in which a spring-pressed plunger 29 is received and is adapted to slide. The head of this plunger is held in engagement with the end of the bearing member 11 by means of the spring 30, and is thus caused to remain in such engagement notwithstanding the transverse and rocking movements of the channel guide. Accordingly, heat is conducted directly from the bearing member 11, through the plunger 29, the plate 26 and the shank of the channel guide, so that the channel guide and its shank are kept hot by direct metallic conduction.

While the invention has been herein illustrated and described in its preferred embodiment, it will be understood that except as hereinafter defined in the claims the invention is not limited to any particular machine or particular construction and arrangement of parts.

The nature and scope of the present invention having been indicated and its preferred embodiment having been specifically described, what is claimed as new is:

1. A waxed thread sewing machine having, in combination, a looper, a channel guide, a heating body, a looper carrier in contact therewith, a channel guide carrier and a conductive metallic connection for heating the channel guide carrier directly from the heating body.

2. A sewing machine having, in combination, a channel guide, means for supporting and actuating the channel guide, a stationary heating body, and a spring-pressed member conductively connecting said means and the heating body to conduct heat to the channel guide.

3. A sewing machine having, in combination, a looper, a channel guide, a cylindrical bearing member and heating body, a looper carrier movably supported on said body, means for supporting and actuating the

channel guide, and a conductive metallic connection between said body and said means.

4. A sewing machine having, in combination, a looper, a looper carrier, a cylindrical bearing for said looper carrier, means for sliding and rocking said looper carrier on the bearing, a steam passage formed in one end of said bearing through which steam is passed to heat the looper, a channel guide, a channel guide carrier having a recess formed therein, and a plunger seated in said recess and engaging the other end of said bearing, whereby the channel guide is heated through metallic conductivity.
5. A sewing machine having, in combination, a looper, a looper carrier, a cylindrical bearing for said looper carrier, means for sliding and rocking said looper carrier on said bearing, a steam passage formed in one end of said bearing through which steam is passed to heat the looper, a channel guide, a channel guide carrier having a recess formed therein, a plunger seated in said recess and adapted to engage the other end of the bearing of the looper carrier, and a spring for holding said plunger in engagement with said bearing in all positions of the channel guide, whereby the channel guide is heated during its movement.
6. A sewing machine having, in combination, a looper, a looper carrier, a cylindrical bearing for said looper carrier, means for

sliding and rocking said looper carrier on the bearing, and heating devices for said looper comprising means for passing steam into the bearing of the looper carrier, said means including inlet and outlet steam passages formed in one end of said bearing and extending through a part of the length of said bearing.

7. A sewing machine having, in combination, a looper, a looper carrier comprising two sleeves connected by a yoke, a cylindrical bearing member embraced at its end portions by the sleeves of said carrier, devices connected to said yoke, means for actuating said devices to rock and slide said looper carrier on its bearing, and means for heating said bearing, whereby heat is conducted to the looper through the sleeves of the looper carrier.

8. A sewing machine having, in combination, a looper, a looper carrier comprising two sleeves connected by a yoke, a cylindrical bearing member embraced at its end portions by said sleeves, a block secured to said yoke, means engaging said block to slide the looper carrier on its bearing, an upstanding arm on said yoke, means engaging said arm to rock the looper on its bearing, and means for heating said bearing whereby heat is conducted to the looper through the sleeves of the looper carrier.

ANDREW EPPLER.
